DESIGN FOR A FAN

Andrew S. Knapp, St. Louis, Mo., assignor to Knapp-Monarch Company, St. Louis, Mo., a corporation of Missouri

Application July 14, 1936, Serial No. 63,838

Term of patent 7 years

To all whom it may concern:

Be it known that I, Andrew S. Knapp, a citizen of the United States, and a resident of the city of St. Louis, and State of Missouri, have invented a new, original, and ornamental Design for a Fan, of which the following is a specification, reference being had to the accompanying drawing, forming part thereof.

I claim:

The ornamental design for a fan, as shown and described.

ANDREW S. KNAPP.
